SAIL EDGE SECURING FIXTURE

Roger E. Joys and John E. Joys, Whitefish Bay, and Arnold F. Meyer, Wauwatosa, Wis., assignors to Joys Brothers Company, Milwaukee, Wis., a corporation of Wisconsin

Application February 17, 1939, Serial No. 256,972

1 Claim. (Cl. 114—112)

This invention relates to improvements in sail edge securing fixtures.

In sail boats the mast and boom are both equipped with longitudinally extending tracks to slidably receive spaced apart brackets carried by the spaced apart portions of the adjacent edges of a sail. This arrangement is necessitated by virtue of the fact that the sail must be raised and lowered relative to the mast and must be susceptible of longitudinal movement relative to the boom. It is furthermore essential that besides the sliding movement permitted as between the tracks and the brackets the sail must be able to swing or flutter relative to the slide brackets. According to standard practice, the desired edge portions of a sail are attached to the slide brackets for the mast and boom tracks by means of heavy twine sewed through the bracket loops and interlaced with the strands of the rope binding on the sail edges. This construction required slow and tedious hand work in the securement of the twine loops and besides being relatively expensive because of the nature of the work required, the sewed and interlaced twine connecting loops had a weakening effect on the rope binding and on the sail because of being passed through the same.

With the above in mind, it is a primary object of the present invention to provide improved sail edge securing fixtures wherein the rope bound edge portions of a sail may be quickly and swingably secured to slide brackets by means of malleable clasps.

A further object of the invention is to provide a sail edge securing fixture wherein a malleable U-clasp is swingably embraced with a slide fixture and is clampingly engaged with a rope bound edge portion of a sail, eliminating the necessity for hand sewn twine connecting means and providing for a quickly applied and very secure attaching means which does not weaken or impair the sail edge.

A further object of the invention is to provide a sail edge securing fixture composed of two movably connected elements, one of which slidably engages a mast or boom track and the other of which clampingly engages a bound portion of a sail edge, both of said elements being connected together so as to permit pivotal movement of one relative to the other in several directions.

A further object of the invention is to provide a sail edge securing fixture which can be assembled, applied and secured to the respective portions of a mast and sail very expeditiously and easily.

A further object of the invention is to provide a sail edge securing fixture which is of very simple construction, is inexpensive to manufacture and install, is strong and durable, which permits the desired movements of a sail relative to a mast and boom, and which is well adapted for the purposes described.

With the above and other objects in view, the invention consists of the improved sail edge securing fixture, and its parts and combinations as set forth in the claim, and all equivalents thereof.

In the accompanying drawing, in which the same reference characters represent the same parts in all of the views:

Fig. 1 is a fragmentary side view of a sailboat mast having a sail slidably attached thereto by means of the improved sail edge securing fixtures;

Fig. 2 is a detail cross-sectional view taken on line 2-2 of Fig. 1; and

Fig. 3 is a detail vertical sectional view through the track on a mast and showing the applied fixture in longitudinal section.

25 Referring more particularly to the drawing, it will appear that the numeral 5 designates the mast of the sailboat to which a sail 6 has its inner edge slidably and swingably secured. The means for securing the inner edge of the sail 6 which 30 has the usual rope binding 7, comprise a plurality of the improved sail edge securing fixtures designated generally by the numerals 8. Each of the fixtures comprises two pivotally joined elements including a slide bracket 9 and a malleable U-clasp 10.

The sail boat mast 5 is provided with a flanged vertical track 11 of the usual form. The opposed flanges of the track are outwardly offset from the surface of the mast and the track is secured to the mast by screws 12 having their head portions lodged within the central recess of the track. Each slide element of a fixture 8 is provided with opposite grooved or recessed flanges 13 to slidably embrace the side flanges of the track 11. The medial portion of the slide bracket is of curved formation and offset outwardly. Through opposite walls of said curved portion, openings are formed to provide an outwardly curved strap 14. The inner face of the strap, where it meets the stock of the fixture, is curved on a suitable radius as at 15.

The clasp element 10 of a fixture is formed of malleable metal and is U-shaped. Initially its jaw or arm portions are relatively widely spread. A clasp element is assembled with a

slide bracket 9 by passing an arm of the clasp through the openings in a slide bracket until the mid-portion of the clasp embraces the strap 14 of the slide bracket as shown in the drawing. The rope bound edge portion of the sail is then inserted between the spread jaw portions of the malleable clasp and is registered with the rounded portions of the same, as best shown in Fig. 2. By means of a suitable tool, the jaws of the clasp are then forced toward one another and into tight clamping engagement with the rope bound edge portion of the sail edge. The small prongs 18 on the inner faces of said portions of the clasp bite into the rope and fabric and additionally aid in effecting a secure engagement of the clasp with the sail edge.

Obviously a number of said fixtures may be applied at suitably spaced points to edge portions of the sail. The slide brackets 9 are free to move longitudinally on the track 11 in the usual manner and the sail 6 is, therefore, slidably mounted by these fixtures to the mast track. In addition, each clasp element 10 is free to pivot in a horizontal plane relative to the strap 14 of its slide bracket 9. Also, because of the inner convex surface 17 of the medial portion of the clasp and because of the enlarged openings in the bracket having rounded portions adjacent the ends of the strap 14, each clasp can addi-

tionally have a limited vertical pivotal movement relative to the slide bracket.

The improved sail edge securing fixtures are inexpensive to manufacture and furthermore may be assembled and applied to a sail edge much more quickly and effectively, and at a lesser cost than was possible with the old types of sail edge securing means. The fixtures are furthermore of simple and novel construction and are well adapted for the purposes set forth.

What is claimed as the invention is:

A sail edge securing fixture, comprising a slide bracket for slidably mounting on a track, said bracket having an outwardly offset curved strap with an opening adjacent the strap, the ends of the strap also being curved to provide curved boundaries for said opening, and a U-shaped malleable clasp, transversely curved and medially engaged by the outwardly offset curved strap, the clasp being limitedly horizontally and vertically pivotally movable on said strap, the outer ends of the arms of said clasp being formed with prongs whereby the ends of said arms may clampingly embrace and bite into only a rope bound edge portion of a sail.
